UNITED STATES PATENT OFFICE.

GEORGE H. F. HOLY, OF PITTSBURGH, PENNSYLVANIA, ASSIGNOR TO WESTINGHOUSE ELECTRIC AND MANUFACTURING COMPANY, A CORPORATION OF PENNSYLVANIA.

JOURNAL-BOX FOR DYNAMO-ELECTRIC MACHINES.

1,323,281.

Specification of Letters Patent.

Patented Dec. 2, 1919.

Application filed January 5, 1915. Serial No. 574.

To all whom it may concern:

Be it known that I, GEORGE H. F. HOLY, a citizen of the United States, and a resident of Pittsburgh, in the county of Allegheny 5 and State of Pennsylvania, have invented a new and useful Improvement in Journal-Boxes for Dynamo-Electric Machines, of which the following is a specification.

My invention relates to journal boxes for 10 dynamo-electric machines, and it has special reference to bearing-housings and supporting means therefor in electrical locomotives and the like.

One of the objects of my invention is to 15 provide a simple, compact and rugged bearing-housing and a supporting-frame member therefor comprising a locomotive side-frame, for example.

Another object of my invention is to provide 20 a structure of the above-indicated character which may be readily dismounted without disturbing adjacent apparatus beneath the floor of the locomotive and with a minimum of inconvenience, time and labor.

In the prior art, bearing-housings have 25 been assembled in supporting frames by means of a relatively large number of bolts that extend substantially parallel to the axis of the motor shaft. As a result, the removal 30 of housings has required considerable longitudinal space, which, in many instances, could be obtained only by the removal of adjacent apparatus.

According to my present invention, I provide 35 a locomotive side-frame, or a motor frame having a recess of substantially circular contour, with a shaft bearing housing adapted to fit in the recess of the frame and to be secured therein by means of a pair 40 of bolts located on the respective sides of the shaft and extending through the housing and into the frame in a plane substantially perpendicular to the shaft. Both the bearing and the housing are preferably of a split 45 type wherein the top parts may be first removed and then the lower part of the bearing may be readily rotated out of the housing. If desired, the lower part of the housing may also be rotated out of the frame recess to the 50 top of the shaft and taken out. The overhauling of the bearing and also of the housing, if desired, may thus be readily accomplished without disturbing adjacent apparatus on the locomotive.

In the accompanying drawing, Figure 1

is a view, chiefly in end elevation but with parts broken away, of a dynamo-electric machine and a locomotive side-frame constructed in accordance with my invention; Fig. 2 is a transverse sectional view taken on the line II—II of Fig. 1, parts being broken away; Fig. 3 and Fig. 4 are similar sectional views taken on the lines III—III and IV—IV, respectively, of Fig. 1; Fig. 5 is a view, in end elevation, of a dynamo-electric machine constructed in accordance with a preferred form of my invention; and Fig. 6 is a view, in side elevation, with parts shown in section, of the structure illustrated in Fig. 5.

Referring to the drawing, the structure here shown comprises a suitable supporting member, such as a locomotive side-frame 1, that is provided with a suitably located machined recess 2 of circular contour and a plurality of relatively small side openings 3 and 4 located beneath the recess 2 for a purpose to be described; a dynamo-electric machine, of any suitable type, comprising a stator 5 which may be secured to the side 70 frame 1 by means of a plurality of bolts 5^a, a rotor 6 that is provided with a centrally-located shaft 6^a, and a split bearing-housing 7, having split bearing brasses 7^a and 7^b, for suitably supporting the shaft 6^a and 75 adapted to fit within the recess 2 of the side frame 1.

The bearing-housing 7 comprises an upper cap member 8 and a lower member 9 which fits directly in the recess 2. The cap member 8 may be secured to the member 9 by means of transversely disposed through-bolts 10, and the lower member 9 is secured to the side-frame 1 through the agency of a plurality of stud-bolts 11 which extend from 80 upwardly-projecting side-members 12 that are located on the respective sides of the cap member 8, through the member 9 and the side-frame 1 to the side openings 3 and 4, respectively. A plurality of suitable nuts 13^a are screwed on the upper ends of the bolts 11, and other nuts 13^b are disposed upon the lower ends of the bolts within the openings 3 and 4. The bolts 11 thus extend as chords of the circular recess 2, or in 85 other words, are disposed substantially perpendicular to the axis of the shaft 6^a.

Assuming the parts to occupy the positions shown the method of disassembly is as follows: The shaft 6^a may first be suit- 100

ably externally supported, by means of a lifting jack, for example. The upper cap member 8 may be removed by taking out the bolts 10, and the upper bearing brass 7^a 5 may also be taken out. The bolts 11 may next be removed, whereupon the lower member 7^b may be rotated out of the housing, and, if desired, the lower member 9 of the bearing-housing may be rotated out of the 10 recess 2 to the upper side of the shaft 6^a and completely removed. However, in some types of machines it may be impracticable to provide sufficient clearance to permit such rotative movement of the housing, but this 15 will probably not constitute any great disadvantage, inasmuch as a removal of the complete housing is not often required. In any case, the removal of the bearing in the manner recited, may readily and conveniently be provided for. The convenience and the time and labor-saving qualities of the construction hereinbefore described is thus evident. Moreover, in case the lower member 9 of the bearing-housing becomes 20 broken, a new member may be constructed to the accurate dimensions of the machined recess 2 and, consequently, the position of the rotor 6 within the stator 5 may be made exactly the same as was the case with the 25 old housing member 9.

Reference may now be had to Figs. 5 and 6, wherein the structure shown comprises a motor half-frame 14 having a centrally-located machined end recess 15, a stator member 16 having a centrally-located shaft 16^a, top-end-plates 17 and a bearing-housing 18.

The housing 18 comprises an upper cap member 19 and a lower member 20 that fits in the frame recess 15. The member 20 is 40 provided with a pair of apertured side-members or projections 21 between which the cap member 19 rests. A pair of corresponding apertured lugs 22 are disposed on the motor frame 14 near the recess 15. A 45 pair of through-bolts 23 respectively extend through the lugs 22 and the corresponding projections 21, and a pair of suitable nuts 24 may be screwed on the threaded ends of the bolts 23, which of course, may 50 extend either upwardly or downwardly, as may be found convenient. A suitable key member 25 may also be located near the bottom of the recess 15 to aid in positioning the member 20. Although the bearing brasses are not shown, it will be understood 55 that they are employed in a similar manner to that shown in Figs. 1 and 4. For securing the cap member 19 to the lower member 20, a plurality of through-bolts 26 may be 60 employed.

A single pair of bolts that extend substantially perpendicular to the shaft 16^a thus secure the two parts of the bearing housing together.

65 The method of disassembly of the struc-

ture just described will be readily comprehended by reason of its similarity to the structure shown in Fig. 1 and from the corresponding description.

I do not wish to be restricted to the specific structural details or arrangement of parts herein set forth, as modification thereof may be made within the spirit and scope of my invention. I desire, therefore, that only such limitations shall be imposed as are indicated in the appended claims.

I claim as my invention:

1. A shaft bearing comprising a stationary semi-circularly recessed supporting frame, a lower bearing-housing member secured within the recess of said frame by means accessible entirely from the exterior of said frame, and an upper member secured to said lower member independently of said frame.

2. A shaft bearing comprising a supporting frame having a recess, a split bearing housing seated in said recess, a split bearing inclosed within said housing, a plurality of bolts extending through the parts of said housing for securing the same together, and separate bolts extending through only one portion of said housing and said frame for securing said housing within said recess.

3. A shaft bearing comprising a stationary frame having a substantially semi-cylindrical recess concentric with the axis of the shaft and an exterior flange extending laterally from said recess, a semi-cylindrical lower bearing member seated within said recess, a plurality of substantially parallel bolts extending through said lower member and said flange for securing said member in place, and a bearing cap secured to said lower member.

4. A shaft bearing comprising a stationary frame having a substantially semi-cylindrical recess therein concentric with the axis of the shaft, a lower bearing member seated in said recess, means for preventing the lateral displacement of said member, a plurality of bolts extending through said member and a portion on the exterior of said frame for securing said member in place, and a bearing cap positioned between said bolts and secured to said member, said cap being independently removable.

5. A shaft bearing comprising a frame having a substantially semi-cylindrical recess, a laterally extending flange around said recess, a lower bearing member seated within said recess, a plurality of substantially parallel bolts extending through said member and said flange to secure said member in place, said member having upwardly extending lugs through which said bolts pass, and a cap disposed between said lugs and secured only to said member.

6. A shaft bearing comprising a support-

- ing frame having a recess of substantially cylindrical contour, a split bearing housing having a lower member seated within said recess, said lower housing member having 5 a recess for containing oil on each side of the shaft, a plurality of bolts for securing said lower member in place, a cap for said housing, and means independent of said bolts for securing said cap in place.
- 10 7. The combination with a supporting frame member having a recess, of a split bearing-housing disposed therein, a split bearing inclosed within said housing, and a plurality of bolts extending through said 15 frame member and said housing in a common plane thereof, whereby the top members of the housing and bearing may be removed and the lower bearing member then rotated out of the housing.
- 20 8. The combination with a supporting frame member having a recess of circular contour, of a split bearing-housing disposed therein and comprising an upper and a lower member and a plurality of bolts for 25 securing the members together, a pair of coöperating bearing-brasses respectively inclosed within said housing members, and a pair of bolts extending through said frame member and the lower housing member in 30 a common plane thereof, whereby, upon removal of said bolts, the upper housing member and the upper bearing-brass may be first removed and then the lower bearing-brass and the lower housing member may be ro- 35 tated substantially 180° and also removed.
9. The combination with a locomotive side-frame having a shaft bearing seat therein of substantially semi-cylindrical contour concentric with the axis of the shaft, of a motor-shaft bearing mounted in 40 said seat and comprising a lower housing member, bolts parallel to the plane of said side-frame for securing said housing member within said bearing seat, and an upper housing member secured to said lower mem- 45 ber.
10. The combination with a locomotive side-frame having a shaft bearing recess therein of substantially semi-cylindrical contour concentric with the axis of the 50 shaft, of a motor-frame member secured to the interior of said side-frame adjacent said bearing recess, a motor-shaft bearing mounted in said recess and comprising a lower housing member, bolts parallel to the 55 plane of said side-frame and accessible entirely from the exterior side thereof for securing said lower housing member within the recess of said side-frame, an upper housing member, and bolts parallel to the first- 60 mentioned bolts for securing the upper housing member to the lower housing member.

In testimony whereof, I have hereunto subscribed my name this 30th day of Dec., 65 1914.

GEORGE H. F. HOLY.
